(57) **CLAIM**

The ornamental design for a card case, as shown and described.

DESCRIPTION

FIG. 1 is a top, exploded, perspective view showing the first embodiment in a partially open state, showing my new design;

FIG. 2 is a bottom, exploded, perspective view showing the first embodiment in a partially open state;

FIG. 3 is a front, exploded view showing the first embodiment in a partially open state;

FIG. 4 is a rear, exploded view showing the first embodiment in a partially open state;

FIG. 5 is a left side, exploded view showing the first embodiment in a partially open state;

FIG. 6 is a right side, exploded view showing the first embodiment in a partially open state;

FIG. 7 is a top, exploded view showing the first embodiment in a partially open state;

FIG. 8 is a bottom, exploded view showing the first embodiment in a partially open state;

FIG. 9 is a top perspective view showing the first embodiment in a closure state;

FIG. 10 is a top, exploded perspective view showing the first embodiment in a split state;

FIG. 11 is a top perspective view showing the second embodiment in a partially open state;

FIG. 12 is a bottom perspective view showing the second embodiment in a partially open state;

FIG. 13 is a front view showing the second embodiment in a partially open state;

FIG. 14 is a rear view showing the second embodiment in a partially open state;

FIG. 15 is a left side view showing the second embodiment in a partially open state;

FIG. 16 is a right side view showing the second embodiment in a partially open state;

FIG. 17 is a top view showing the second embodiment in a partially open state;

FIG. 18 is a bottom view showing the second embodiment in a partially open state;

FIG. 19 is a top perspective view showing the second embodiment in a closure state; and,

FIG. 20 is a top perspective view showing the second embodiment in a split state.

The broken lines in the drawings illustrate the portions of the card case, which form no part of the claimed design. The dot-dash-dot broken lines representing stitching are part of the claimed design.

1 Claim, 20 Drawing Sheets
